UNITED STATES PATENT OFFICE

168,848

DISPENSING CAN

William Mack, Pittsburgh, Pa., assignor to the
United States of America as represented by the
Secretary of the Army

Application June 9, 1952, Serial No. 20,101

Term of patent 3½ years

(CL. D58—17)

To all whom it may concern:

Be it known that I, William Mack, a citizen of the United States, residing at Pittsburgh, in the county of Allegheny and State of Pennsylvania, have invented a new, original, and ornamental Design for a Dispensing Can, of which the following is a specification, reference being had to the accompanying drawings, forming a part thereof.

Figure 1 is a perspective view of a dispensing can, showing my new design;

Figure 2 is a plan view thereof;

Figure 3 is a fragmentary side elevational view thereof; and

Figure 4 is a fragmentary side elevational view thereof but showing the parts in the dispensing position.

The dominant features of the design are shown in full lines.

I claim:

The ornamental design for a dispensing can, substantially as shown and described.

WILLIAM MACK.
